HAIR CLIPPER

Burton J. Lipman, University City, Mo.

Application January 8, 1954, Serial No. 402,911

10 Claims. (Cl. 30—29.5)

1

This invention relates generally to improvements in a hair clipper, and more particularly to improvements in a hair-cutting device adapted to remove hair growth from small cavities such as the nostrils or ear openings.

An important object of the present improvements is to realize a clipper device for the purposes mentioned which may be easily and accurately operated by one hand to effect removal of hair from nostril or ear cavities with precision and without any danger of severing the skin. Briefly stated, the device is comprised of a tubular body having an end portion of reduced cross sectional area, the end portion having a plurality of slots, and a plunger reciprocably received in and movable along the longitudinal axis of the body. The plunger includes a cutting head that closely fits the reduced end portion, and coacts therewith to sever hairs projecting through the slots.

Another important objective is realized in providing a series of particularly arranged slots in a tubular portion of the hair-cutting device, and in providing a cutting head having a sharp peripheral cutting edge adapted to wipe the edges defining the slots to sever the hairs incident to forward longitudinal movement of the head. Another advantage is afforded in the provision of a dished formation in the cutting head immediately adjacent the cutting edge which is adapted to collect the hairs after severance, thus clearing the cutting edge and slots for subsequent hair cutting action upon reciprocable actuation of the head, the structural arrangement affording a self-cleaning effect.

A still further important object is to provide a clipper device that is simple and durable in construction, is inexpensive to manufacture, and which consists of relatively few parts that may be quickly and easily assembled for precise and efficient operation.

The foregoing and numerous other objects of the invention will more clearly appear from the following detailed description of a presently preferred embodiment, particularly when considered in connection with the accompanying drawing, in which:

Fig. 1 is an enlarged side elevational view of the hair clipper;

Fig. 2 is a longitudinal sectional view as taken along line 2—2 of Fig. 1;

Fig. 3 is a view in cross section as taken along line 3—3 of Fig. 1, and

Fig. 4 is a perspective view of the cutting head and connecting rod of the plunger mechanism.

2

Referring now by characters of reference to the drawing, and first to Figs. 1 and 2, it will be apparent that the hair-cutting device, generally indicated at 10, consists partly of a tubular body 11 having a forward end portion 12 of relatively reduced diameter. The tubular body 11 is provided with a shoulder 13 (Fig. 2), and a depressed annular bead 14 slightly spaced from shoulder 13. A washer 15 is located between and secured by shoulder 13 and bead 14, the washer 15 defining the rear of reduced end portion 12. Additional purposes and functions of washer 15 are later described in detail.

The end portion 12 of tubular body 11 is provided with a plurality of elongate slots 16, the slots 16 being arranged in a predetermined regular pattern of four longitudinal rows. As is more clearly shown by Fig. 3, the rows of slots 16 are equidistantly spaced around tubular end portion 12. Each slot 16 of each row is located directly opposite a corresponding slot 16 of each adjacent row, and each slot 16 is disposed so that the side edges defining the slots are arranged obliquely to the longitudinal axis of tubular body 11.

A plunger mechanism, generally referred to at 17, is slidably received and mounted for reciprocable actuation in tubular body 11. The plunger 17 includes a cylindrical cutting head 20 that closely fits the bore of reduced end portion 12. Formed integral with cutting head 20, is a connecting rod 21 that extends rearwardly through a central aperture provided in washer 15. The rear end of rod 21 is provided with threads 22 for threaded connection to an actuating button 23. It will be noted that button 23 is of a diameter that closely approximates the internal diameter of tubular body 11, and is slidably received therein.

The button 23 is provided with an annular shoulder 24 that constitutes a thumb rest, and that coacts with the rear end of tubular body 11 to limit the extent of retraction of the plunger mechanism 17. A compression spring 25 is located in tubular body 11, one end of which abuts washer 15, while the opposite end seats on the forward end of button 23, the spring 25 being arranged about rod 21. Normally the spring 25 acts to urge the plunger mechanism 17, and hence cutting head 20 rearwardly to the position shown in Fig. 2. In this extended position, the rear portion of cutting head 20 abuts washer 15, and hence head 20 is confined to operation in reduced end portion 12.

To enable one hand operation of the hair-cutting device, the rear end of tubular body 11 is

provided with an annular flange 26 that is of sufficient dimensions to be gripped between the first two fingers of the hand. When flange 26 is gripped in the manner described above, the button 23 may be depressed by the thumb along the longitudinal axis against the loading of spring 25 until shoulder 24 abuts flange 26. The outer surface of tubular body 11 may be knurled in the region adjacent flange 26, as is shown in Fig. 1, to afford a more effective grip for the fingers.

The cutting head 20 includes a sharp, peripheral cutting edge 27 along its forward margin which is adapted to wipe the lateral edges defining slots 16 so as to sever hair projecting through the slots and into reduced end portion 12. From the perspective view of Fig. 4, it is seen that the forward portion of cutting head 20 is provided with a concave dished formation 30 immediately adjacent peripheral cutting edge 27, the formation 30 being adapted to collect the hair after severance by cutting edge 27, hence acting to clear slots 16 and edge 27 to realize a self-cleaning effect.

The operation and functional use of the device is thought to have become fully apparent from the foregoing detailed description, but for completeness of disclosure, it will be noted that tubular body 11 is gripped between the first two fingers, and button 23 is actuated by the thumb. The reduced end portion 12 is inserted into the nostril, and the button 23 is depressed. As a result, head 20 is moved longitudinally forward so that cutting edge 27 wipes the edges defining slots 16, hence severing hairs projecting into slotted end portion 12. The severed hairs fall into dished formation 30, and are collected for subsequent removal. After head 20 reaches the end of its forward cutting stroke, as determined by engagement of shoulder 24 with flange 26, the button 23 is released by the thumb. Consequently, the spring 25 acts to return cutting head 20 and button 23 to the extended position shown by Fig. 2. It is seen that as button 23 is actuated by the thumb, the cutting head 20 is reciprocably moved in slotted end portion 12. After removal of end portion 12 from the nostril, the head 20 may be moved to its forwardmost position in end portion 12, and the hairs emptied from dished formation 30 through the open forward end of tubular portion 12.

Although the invention has been described by making detailed reference to a single preferred embodiment, such detail is to be understood in an instructive, rather than in any restrictive sense, many variants being possible within the scope of the claims hereunto appended.

I claim as my invention:

1. A device for clipping hair comprising a tubular body having an end portion of reduced cross sectional area, said reduced end portion being provided with a series of slots, and a plunger reciprocably received in the tubular body, the plunger including a cutting head closely fitting the reduced end portion, and coacting therewith to sever hairs projecting through said slots.

2. A device for clipping hair comprising a tubular body having an end portion of relatively reduced diameter, said reduced end portion being provided with a series of slots, the slots being arranged obliquely to the longitudinal axis of the tubular body, and a plunger reciprocably received in said body, said plunger including a cylindrical cutting head closely fitting the bore of said reduced end portion, said head coacting with said

reduced end portion to sever hairs projecting through said slots.

3. A device for clipping nasal hair comprising a tubular body having an end portion of relatively reduced diameter, said reduced end portion being provided with a series of elongate slots, and a plunger reciprocably received in the tubular body, said plunger including a cutting head closely fitting the bore of said reduced end portion, and including an actuating button extending outwardly of said tubular body, said cutting head coacting with said reduced end portion to sever hairs projecting through said slots upon reciprocal movement of said actuating button.

15 4. A device for clipping nasal hair comprising a tubular body having an end portion of relatively reduced diameter, said reduced end portion being provided with a series of elongate slots, the slots being arranged obliquely to the longitudinal axis of the tubular body, a plunger reciprocably received in said tubular body, the plunger including a cutting head closely fitting the bore of said reduced end portion, and including an actuating button extending outwardly of said tubular body, 20 and spring means disposed in said tubular body and connected to said plunger so as to urge said plunger in an extended position, said cutting head coacting with said reduced end portion to sever hairs projecting through said slots upon reciprocal movement of said actuating button.

30 5. In a device for clipping nasal hair, a tubular body having a relatively reduced end portion, the reduced end portion being provided with a series of elongated slots, a plunger reciprocably received in said tubular body, said plunger including a cutting head closely fitting the bore of said reduced end portion, and including a button extending outwardly of said tubular body, means for retaining the plunger in said body, and spring means disposed in said tubular body and connected to said plunger so as to tend to urge said button in an extended position, said cutting head coacting with the reduced end portion to sever hairs extending through the slots upon depression of actuation of said button.

45 6. In a device for clipping nasal hair, a tubular body having a relatively reduced end portion, the reduced end portion being provided with a series of elongate slots, a plunger reciprocably received in said tubular body, said plunger including a cutting head, said head conforming closely to the bore of said reduced end portion, said head being provided with a sharp peripheral cutting edge adapted to wipe the edges defining said slots with a reciprocating motion, upon actuation of said plunger.

50 7. In a device for clipping nasal hair, a tubular body having a relatively reduced end portion, the reduced end portion being provided with a series of elongate slots arranged obliquely to the longitudinal axis of said body, a cutting head reciprocably received in said reduced end portion, said head including a sharp peripheral cutting edge adapted to wipe the edges defining said slots with a reciprocating motion, whereby to sever hairs projecting through said slots, and means operatively connected to said head and extended outwardly of the rear of said tubular body, said means being adapted to cause reciprocal actuation of said head.

55 8. In a device for clipping nasal hair, a tubular body having a relatively reduced end portion, the reduced end portion being provided with a series of elongate slots arranged obliquely to the longitudinal axis of said body, a cylindrical

cutting head closely fitting the bore of said reduced end portion, said cutting head being provided with a sharp peripheral cutting edge along its forward margin, said cutting edge being adapted to wipe the edges defining said slots to sever hairs projecting through said slots, said head having a transverse forward portion immediately adjacent said cutting edge, and means operatively connected to said head, and adapted to move said head with a reciprocating action substantially the length of said reduced end portion, the transverse forward portion of the head being adapted to deliver the severed hair out of the forward end of said reduced end portion.

9. In a device for clipping nasal hair, a tubular body having an end portion of relatively reduced diameter, the reduced end portion being provided with a plurality of longitudinally arranged rows of elongate slots, said slots being disposed obliquely to the longitudinal axis of said tubular body, a cylindrical cutting head closely fitting the bore of said reduced end portion, said head being provided with a sharp peripheral cutting edge along its forward margin, said cutting edge being adapted to wipe the edges defining said slots to sever hairs projecting through said slots, said head being provided with a concave formation in its forward end portion immediately adjacent said cutting edge, the concave formation being adapted to collect said hairs after severance by said cutting edge, a button operatively connected to said cutting head and extended partly out of said tubular body, said button being adapted to move said head with a reciprocating action substantially the length of said reduced end portion, the head being adapted to be moved to the forward end of the reduced end portion so as to dispose of the hair clippings collected in said formation.

10. In a device for clipping nasal hair, a tubular body having an end portion of relatively reduced diameter, the reduced end portion being provided with a plurality of longitudinally arranged rows of elongate slots, said slots being disposed obliquely to the longitudinal axis of said tubular body, a plunger received in said body, said body including a cutting head that closely fits the bore of said reduced end portion, a washer disposed at the rear of the reduced end portion, said washer confining the cutting head to reciprocating movement in the reduced end portion, a button slidably received in said tubular body, said button normally extending outwardly of said body, and a plunger rod operatively connecting said cutting head and said button, a spring means disposed in said body, one end of said spring means abutting said washer, the opposite end of said spring means abutting said button, said spring means being adapted to tend to urge said button in an extended position, and to urge said cutting head rearwardly to abut said washer, said cutting head being provided with a sharp peripheral cutting edge along its forward margin, said cutting edge being adapted to wipe the edges defining said slots to sever hairs projecting through said slots, incident to forward longitudinal movement of said head, the forward portion of said head being provided with a concave dished formation immediately adjacent said cutting edge, said formation being adapted to collect the hairs after severance by said cutting edge, the cutting head being movable forwardly in a cutting stroke upon depressing actuation of said button, the head being movable to the forward end of the reduced end portion to empty the dished formation.
